Filed June 21, 1973, Ser. No. 372,082

Term of patent 14 years

Int. Cl. D14—01

U.S. Cl. D56—4 R

FIG. 1 is a front elevational view of a phonograph, showing my new design in which the pattern indicated by the hatching in the rectangle in the center of the top half of the figure is continuous throughout the rectangle; FIG. 2 is a right side elevational view;

FIG. 3 is a left side elevational view;

FIG. 4 is a top plan view;

FIG. 5 is a rear elevational view, drawn on a reduced scale; and

FIG. 6 is a fragmentary sectional view taken along the line 6-6 of FIG. 2 and drawn on an enlarged scale.

I claim:

The ornamental design for a phonograph, substantially as shown and described.
